LINKED JAW PIPE WRENCH WITH ADJUSTABLE LINK PIVOT

Filed March 12, 1945

UNITED STATES PATENT OFFICE

2,448,221

LINKED JAW PIPE WRENCH WITH
ADJUSTABLE LINK PIVOT

Oscar V. Jones, Dallas, Tex.

Application March 12, 1945, Serial No. 582,231

2 Claims. (Cl. 81—67)

1

This invention relates to wrenches and tongs and it has particular reference to break-out tongs for well pipe.

The objects of the invention are; first: to provide jaws whose fulcrum point is displaceable to effect basic adjustment of the jaws to adapt the tong to work of different diameters; second: to provide a saddle yoke for holding the jaws in adjusted position; third: to provide complementary inserts for the jaws to adapt them to work of comparatively small diameter, and fourth: to provide a handle so pivoted to one of the jaws opposite the fulcrum point of the latter that certain protuberances carried by and opposing the pivotal point of the handle will, on the one hand, limit the pivotal movement of the handle to govern the positioning of the tong with respect to the work and on the other hand, will secure the jaws about the work with increasing uniform pressure circumferentially distributed, in corresponding relation to pressure imposed on the handle.

With the foregoing objects as paramount, the invention has further reference to certain features of accomplishment which will become apparent as the description proceeds, taken in connection with the accompanying drawings wherein:

Figure 1 is a perspective view of a tong constructed according to the invention, showing the jaws closed.

Figure 2 is a perspective view of the opposite side of the tong, slightly enlarged, showing the jaws slightly open, a portion of one of the jaws being broken away to show the end of a work engaging slip.

Figure 3 is a plan view, partly in section.

Figure 4 is an end elevational view of the tong.

Figure 5 is a detail perspective view of the saddle yoke, and

Figure 6 is a detail perspective view of the fulcrum block.

Continuing with a more detailed view of the drawing, reference numeral 10 denotes a major work engaging jaw whose pivotal relationship with the minor work engaging jaw 11 is effected through the medium of a fulcrum block 12, shown in detail in Figure 6. The pivotal end of jaw 10 is formed to define a housing 13, in which the block 12 is slidably disposed. The jaw 11 has corresponding ears 14 formed thereon between which the end of the block 12 is interposed and pivoted by means of a pin 15, passing through openings in the ears 14 and an aperture 16 in the tail of the block 12. It is apparent that through this arrangement the jaws 10 and 11

2

may be relatively displaced a distance equal to the spacing between the housing 13 of jaw 10 and the head 17 of the block 12 which limits the degree of displacement. The jaws may thus be adapted to work of large diameter.

In order to secure the jaws against the displaced position described, a saddle yoke such as shown in Figure 5 is employed and which consists of a yoke formed of arms 18 which straddle the block 12 between the housing 13 of jaw 10 and the head 17 of the block. The wedging action thus afforded by the yoke securely holds the jaws against relative displacement at their pivotal point, yet is ineffective to prevent free and unrestricted pivotal movement of jaw 11 on the pin 15. When the yoke 18 is in the described position, the jaws 10 and 11 are in relative positions for application to work of smaller diameter.

The yoke 18 is secured to the housing 13 of the jaw 10 through the medium of a tail portion 19, in which there is provided a slot 20, through which a bolt 21 is passed into a threaded opening in the housing 13, so that the tail portion 19 may be longitudinally displaced to adjust the position of the yoke 18 relative to the block 12. During periods when the tong is adapted for work of larger diameter, the yoke is removed from the position shown to permit the jaws to be moved apart so that the housing 13 will abut the head 17 of the block 12. The yoke is then replaced, but with the arms 18 thereof bearing on the top of the head 17 of the block. When thus disposed, the yoke obviously functions to hold the jaws apart at their pivotal ends.

At the opposite end of jaw 10, the flanges of the jaw are extended to provide bifurcations 23 between which is pivotally held, by means of pin 22, a handle 24.

The handle 24 has an arm or protuberance 25 which extends between the flanges of the jaw 10 to lie against the body of the jaw in some cases to limit the degree of relative movement of the jaw and handle. On the opposite side of the pivotal point 22 of the handle, there is provided another protuberance 26 which bears upon a cam surface 27, formed upon the body of jaw 11 at its end.

When the jaw 11 is closed upon the work, the handle 24 is actuated to bring the protuberance 26 into engagement with the cam surface 27 and as pressure is increased on the handle, pressure of the jaws is correspondingly increased on the work but such pressure is uniformly distributed about the pipe to obviate tendency to crush the same.

To hold the pipe, and prevent slippage of the jaws thereon, customary toothed inserts 28 are provided in corresponding grooves in the inner surfaces of the jaws, as shown. In cases where it is necessary or desirable to further reduce the effective diameter of the jaws, work engaging segments 29 (Fig. 2) are provided which are each equipped with shoulders 30 at each end, receivable in correspondingly shaped recesses 31 in the jaws at the ends thereof. This arrangement is shown more particularly in Figure 2 which discloses but one of the removable segments 29 for purposes of illustration. These segments are each recessed at a to accommodate the teeth 29 and may, themselves, be similarly equipped with gripping teeth 32. To hold the segments in place, suitable bolts are passed through the walls of the segments at their mid-sections and through holes 33 in the jaws, with nuts threaded onto their outer ends. The inner heads of the bolts are, of course, countersunk in the inner walls of the segments 29.

In some cases it may be desired to secure the tong onto a pipe section with sufficient clearance between the pipe and jaws to permit the latter to ratchet thereon. To lock the jaws against release from the pipe while the tong is reciprocated to rotate the pipe, a set screw 34 is threaded through the arm 25 to bear against the jaw 10, as shown in Figure 3 and by setting this screw, relative spacing between the protuberance 26 of the handle and the cam surface 27 of jaw 11 may be predetermined, thus predetermining the degree of greater expansion of the jaws. It is obvious that means other than the screw 34 may be employed for the purpose explained and the screw has been shown for purposes of illustration.

It is apparent also that with but slight, if any modification, the tong described herein may be adapted for use by plumbers, steam-fitters and others engaged in the handling and assembling of pipe and tubing.

Manifestly, the construction as shown and described is capable of some modification and such modification as may be construed to fall within the scope and meaning of the appended claims is also considered to be within the spirit and intent of the invention.

What is claimed is:

1. A pipe wrench comprising a pair of semi-circular pipe engaging jaws, one of which has a handle pivoted to one end thereof and a housing formed on its opposite end, a fulcrum block 6 slidable in said housing having a head on one end and a transverse opening in its opposite end, the other of said jaws having parallel ears between which said block is received, a pivot bolt 10 extending through said ears and the opening in said block, a substantially U-shaped yoke whose parallel arms are receivable by said block to be disposed between the head of the latter and said jaw housing, a tail on said yoke at right angles thereto adapted to bear against said housing and having an elongated slot therein, a bolt 15 extending through said slot into said jaw housing to secure said yoke and to hold said jaws in adjusted pivotal relationship through the medium of said fulcrum block.
2. A pipe wrench comprising a pair of semi-circular pipe engaging jaws, one of said jaws having a handle pivoted on one end, a housing on the opposite end of said jaw, a fulcrum block 20 having a transverse head on one end and adapted 25 to be slidable longitudinally in the housing of said jaw, means pivotally connecting the other of said jaws at one end to the opposite end of said fulcrum block for relative displacement of said jaws, 30 a yoke disposable between the head of said fulcrum block and said jaw housing, a tail formed on said yoke at right angles thereto adapted to bear against said jaw housing and having an elongated slot therein and means passing through said slot into said jaw housing to hold said yoke 35 in adjusted positions.

OSCAR V. JONES.
